BY Drake & Co.

ATTORNEYS.

UNITED STATES PATENT OFFICE.

CHARLES ROSIN, OF NEWARK, NEW JERSEY.

BOUTONNIÈRE, BADGE, &c.

SPECIFICATION forming part of Letters Patent No. 595,655, dated December 14, 1897.

Application filed August 10, 1896. Serial No. 602,265. (No model.)

To all whom it may concern:

Be it known that I, CHARLES ROSIN, a citizen of the United States, residing at Newark, in the county of Essex and State of New Jersey, have invented certain new and useful Improvements in Boutonnieres, Badges, &c.; and I do hereby declare the following to be a full, clear, and exact description of the invention, such as will enable others skilled in the art

5 to which it appertains to make and use the same, reference being had to the accompanying drawings, and to letters of reference marked thereon, which form a part of this specification.

15 This invention relates to certain improvements in that class of badges or boutonnieres in which an artificial flower is provided with movable petal-like parts adapted to be opened away from one another at the will of

20 the wearer to disclose an internal legend or inscription, design or picture concealed between or under said petals.

The objects of the present improvement are to enable the hidden legend or inscription, 25 picture or design to be held or disposed so that when exposed to view on the lapel of the wearer's coat it will be in a plane at right angles to the line of vision, or substantially in line with the stem of the flower, and thus said

30 design will present a full-face view direct to the eye.

Another object is to provide an immovable vertical support for the legend or design plate, so that when said design-plate is glued 35 to the flower and the other movable parts are frequently operated to cover or uncover the design the said design-plate will remain fixed and immovable in vertical relation to its flexible stems or supports. Thus danger of being

40 torn loose is avoided and the durability of the article is increased.

A further object is to provide increased space within the flower for the legend or design without detraction from the natural appearance of the same, thus enabling larger and more clearly-observable letters or characters to be employed in the legend or picture.

Further objects are to reduce the cost of 45 construction, simplify the structure, and thus facilitate its manufacture, and to secure other

advantages and results, some of which may be referred to hereinafter in connection with the description of the working parts.

The invention consists in the improved boutonnière, badge, or the like, and in the arrangements and combinations of parts thereof, all substantially as will be hereinafter set forth, and finally embraced in the clauses of the claim.

Referring to the accompanying drawings, in which like letters of reference indicate corresponding parts in each of the views, Figure 1 is an elevation, and Fig. 2 is a section taken at line *x*, of the framework of the button. Fig. 3 shows in front elevation the article complete on a reduced scale, the parts being in their closed positions. Fig. 4 is a similar elevation, the said parts being in their open positions, in which they are adapted to display the legend, insignia, campaign or other imprint or design. Fig. 5 is a plan of the supporting-plate in blank, having petal-shaped arms adapted to be opened up to provide supports for the flower-like decorative petals to be afterward applied, and also showing a slot adapted to receive a hinge-tongue of a coöperating petal-shaped plate; and Fig. 6 is a plan in detail of the blank petal-shaped coöperating plate last referred to.

55 60 65 70 75 80

In said drawings, *a* indicates the main or body supporting-plate upon which the artificial flower is built. This consists of a piece of sheet metal having, preferably, at three sides thereof integral petal-like arms *b*, which are bent up at or approximately at right angles to the plane of the center part to hold the ornamental petals attached thereto erect. Said arms *b* are preferably made concaveous at their inner sides, so as to give a similar shape to the textile or flexible ornamental petals, such as are employed in artificial-flower work, attached thereto. Being integral with the center part of the body-plate, said arms *b* are substantially rigid and immovable in their relation to one another and with the pin or button-shank and form a group of standards around the point of attachment to said pin, around which in turn an assemblage of flexible ornamental petals are arranged in artistic design or in close imitation to a natural disposition of petals.

85 90 95 100

The textile or otherwise flexible and decorative petals l are fastened around the rigid arms and to one another by cement or other suitable means, so that they maintain a fixed 5 relation to one another and form a comparatively broad field upon which to apply the legend or design. While I ordinarily prefer muslin or such like material in making the ornamental petals, I may employ wax, celluloid, &c.

The ornamental petals fastened around the upwardly-extending arms *b* serve as a vertical support for what I have hereinafter termed a "legend-plate" *i*, on which latter is imprint-
15 ed, impressed, or otherwise applied the picture, words, or design to be exposed from time to time. Being thus supported in a vertical position, or substantially in line with the stem of the flower, when the hinged petals are
20 drawn down the said legend-plate will stand opposite the observer, so that the subject of the imprint will be exposed fully and clearly to direct view.

To the center portion of the said supporting-plate *a*, which is preferably slotted at *c*, is hinged another coöperating plate *d*, preferably provided with a tongue *e*, adapted to be inserted in the slot *c* and turned so as to hold the said coöperating plate upon the plate *a*, as shown in Fig. 2, and admit of a hinge action. The coöperating plate *d* is also inclosed or covered with textile petal-shaped coverings colored in resemblance to the petals of a natural flower, so that the metal portions of the supporting-plates are concealed and only the decorative textile coverings are presented to view both when the flower is opened and when closed.

The body plate or frame *a*, covered with the decorative petals, may be considered to be the body A of the flower, and the hinged plate *d* and its petals may be termed the "legend" or "insignia" cover B.

45 An elastic cord *f* or other form of spring is fastened at its opposite ends to the supporting-plate *a* and upon the coöperating plate *d*, the normal tendency of which spring is to hold the hinged plate closed against the plate *a*. I prefer to arrange this spring as shown
50 in Fig. 2. The opposite ends of the cord are knotted. One end is passed through the perforation *g*, Fig. 5, and the other end is clamped by a tongue *h*, struck up out of the hinged plate *d*, as shown in Fig. 6. Said
55 tongue *h* is simply bent over the elastic cord, forming an eye through which the knotted end cannot be drawn. While the said cord *f* normally holds the hinged plate in its closed position, said plate is adapted to be turned
60 down or opened, as shown in outline in Fig. 2, and to facilitate the opening operation I employ a cord *j*, which is knotted and secured in the perforation *k* of the plate *d* and extends downward therefrom, so as to be easily and
65 conveniently grasped by the hand. When downward draft is brought upon this cord *j*, it is evident that the plate *d* will be drawn

downward against the power of the spring *f*, revealing the legend, inscription, or imprint on the interior of the flower.

The flower may be provided with a suitable stem *m*, whereby it may be held in the button-hole of the coat, which stem may be a pin, as shown in Figs. 1 and 2, or it may be otherwise provided with means for holding the flower to the garment. The stem *m* is preferably fixed to the body portion *A* of the flower so that the petals of the said body portion will stand erect and more or less rigid or stationary upon the garment when the hinged petals are drawn down. 75 80

Upon the interior of the flower, exposed to view when the hinge-plate is opened, is arranged a legend-plate *i*, as shown in Fig. 4. This is preferably of celluloid, although it may be of any other suitable material, and on the surface it has imprinted the legend, inscription, imprint, or design which is to be revealed by the wearer when he draws down the covered hinge-plate *d*. The act of drawing down and revealing the design is intended to act as a surprise to the person facing the wearer of the badge, and thus affords or is the occasion of amusement to both. 9c

The operation of the parts of the device 95 have already been sufficiently explained and a repetition is thought to be unnecessary.

I am fully aware that various modifications of construction may be made in my invention, and therefore I do not wish to be understood as limiting myself to the positive descriptive terms employed, excepting as the state of the art may require. For example, it is not necessary that I limit myself to one hinged petal or collection of petals. 105

Having thus described the invention, what I claim as new is—

1. In combination with the main or body petal-supporting plate of metal having petal-shaped arms, bent up substantially as described from the center portion, said center portion being slotted as at *c*, a hinged metal piece *d*, having a tongue inserted through said slot and turned to form a hinge-eye, ornamental petals inclosing said metal parts, a 115 spring, means for drawing the hinged piece away from the body-frame and petals, and a pin or stem rigidly fastened to the body supporting plate or frame, substantially as set forth. 120

2. The combination with the main or body petal-supporting plate or frame of metal having concavous arms bent up substantially as described from the center portion, said center portion being perforated and having hinged 125 bearings, a piece hinged upon said frame or plate and having a tongue *h*, struck up out thereof, an elastic cord knotted and extending through the perforation of the body-plate and under the tongue *h*, a stem rigidly secured to the body-plate and ornamental petals, all arranged and combined and operating, 130 substantially as set forth.

3. In a badge, the combination with the

body-plate having a perforated center portion with a rigid stem and arms *b*, *b*, *b*, bent up from said center portion, a hinged petal-shaped piece and an elastic cord fastened to 5 said perforated body-plate and hinged piece, substantially as set forth.

4. The improved badge or boutonnière comprising a pin or means of attachment to the garment, a body-plate fixed to said pin and 10 having a collection of rigid or unhinged arms extending in lines substantially parallel with the axial line of said pin, a plate hinged to said body-plate and normally standing in a line substantially parallel with said rigid 15 arms, a spring for holding said hinged arm in said position, a cord attached to said hinged plate for drawing it down from its erect normal position, and ornamental petals held upon and covering said arms and maintaining a 20 permanent relation to one another and ornamental petals covering said hinged plate and movable to and from the permanently-arranged petals to disclose the interior of the flower, substantially as set forth.
- 25 5. The improved badge or boutonnière comprising a pin or means of attachment to the garment, a body-plate fixed to said pin and having rigid or integral arms disposed around the point of attachment to said pin and bent 30 to lie in lines approximately parallel with one

another, a hinged plate, a spring attached to said hinged plate and body-plate to hold said hinged plate normally in a line approximately parallel with the rigid arms, means attached to said hinged plate to draw it away from the 35 rigid arms, ornamental covering-petals attached to the rigid arms and hinged plate to conceal the same from view and a legend or inscription plate seated on the rigid ornamental petals adapted to be uncovered and 40 revealed when the hinged plate and its coverings are drawn down, substantially as set forth.

6. In a boutonnière, a collection of ornamental petals permanently arranged in fixed 45 relation to one another and their supporting-plate and together forming a seat for a legend-plate, and spring-controlled covering-petals, movable in relation to said fixed petals, means for drawing said movable petals away from 50 said fixed petals to uncover and reveal said legend-plate, and said legend-plate fastened to said fixed petals, substantially as set forth.

In testimony that I claim the foregoing I have hereunto set my hand this 5th day of 55 August, 1896.

CHARLES ROSIN.
